TIE-DOWN HOOK FOR PICKUP TRUCK

Kanji Hitomi, 1216 56th Ave.,
Sacramento, Calif. 95831

Filed June 12, 1974, Ser. No. 478,767

Term of patent 14 years

Int. Cl. D8—08

U.S. Cl. D8—229

FIG. 1 is a perspective view of the tie-down hook for pickup truck;

FIG. 2 is a side elevation of the invention;

FIG. 3 is an end elevation of the invention; and

FIG. 4 is a bottom plan view of the tie-down hook for pickup truck.

I claim:

The ornamental design for a tie-down hook for pickup truck, substantially as shown.
